(57) **CLAIM**

The ornamental design for a motion activated light, as shown and described.

DESCRIPTION

FIG. 1 is a perspective view of a motion activated light, in accordance with an embodiment of the present invention. FIG. 2 is another perspective view of the motion activated light of FIG. 1.

FIG. 3 is another perspective view of the motion activated light of FIG. 1.

FIG. 4 is another perspective view of the motion activated light of FIG. 1.

FIG. 5 is a front view of the motion activated light of FIG. 1.

FIG. 6 is a top view of the motion activated light of FIG. 1.

FIG. 7 is a left side view of the motion activated light of FIG. 1.

FIG. 8 is a right side view of the motion activated light of FIG. 1.

FIG. 9 is a rear view of the motion activated light of FIG. 1; and,

FIG. 10 is a bottom view of the motion activated light of FIG. 1.

The broken lines representing coupling members, shown in FIGS. 7, 8 and 10, represent disclaimed subject matter and form no part of the claimed design.
